UNITED STATES PATENT OFFICE.

ADOLPHUS F. EDDY, OF BERKELEY, CALIFORNIA.

COMBINATION-TOOL.

1,356,431.

Specification of Letters Patent. Patented Oct. 19, 1920.

Application filed April 16, 1919. Serial No. 290,389.

To all whom it may concern:

Be it known that I, ADOLPHUS F. EDDY, a citizen of the United States, residing at Berkeley, in the county of Alameda and State of California, have invented new and useful Improvements in Combination-Tools, of which the following is a specification.

This invention relates to a combination tool and particularly to a tool for pulling 10 nails.

One of the objects of the present invention is to provide a simple, substantial and cheaply manufactured combination tool, useful for various purposes but particularly 15 adapted for use in conjunction with a claw hammer when pulling nails, said tool permitting nails to be removed without bending the same, enlarging the nail holes or otherwise mutilating the surface or material 20 into which the nails have been driven.

Another object of the invention is to provide a combination tool which may serve various uses; for instance, that of a carpenter's square, a hammer, a foot rule, a wrench, 25 a nail gage, an anvil, a crowbar or prying tool, and other uses, as hereinafter to be described.

Further objects will hereinafter appear.

The invention consists of the parts and the 30 construction, combination and arrangement of parts as hereinafter more fully described and claimed, having reference to the accompanying drawings, in which—

Figure 1 is a perspective view of the tool; 35 Fig. 2 is a bottom view of the same;

Fig. 3 is a side elevation, showing the use of the tool when pulling nails; and

Fig. 4 is a cross-section on line 4—4, Fig. 3.

Referring to the drawings in detail, and particularly to Fig. 1, it will be seen that the tool consists of a head member A and a pair of triangular-shaped plate sections 2 and 3. The tool is comparatively long and narrow 45 and is preferably constructed of cast steel, malleable iron, or the like. The plate sections 2 and 3 are therefore formed integral with the head A and are in this instance interspaced to form a centrally disposed channel 4. This channel extends from the pointed end 5 of the plate sections up to the head member A, thus separating the same, as shown in Figs. 1 and 2, to permit the plates to straddle a nail when this is to be removed, as will hereinafter be described. 50 The head A is approximately square in shape

when viewed from the side, but it is otherwise narrow so as to reduce the weight of the tool in general as much as possible. The head is provided with a handle opening A', 60 an anvil surface 6, and a pair of grooves 7 and 8 which are employed for the purpose of straightening bent nails. The plate sections 2 and 3 are reinforced or ribbed along the edges, as shown at 9, and the web sections 65 of the plates are provided with openings which permit the tool to be used as a wrench; for instance, the web formed in the plate section 3 is provided with square openings shown at 10 to permit the tool to be applied 70 when removing square-shaped nuts, while the web section of the plate 2 is provided with hexagonal openings to permit the removal of hexagon nuts, the openings in the respective web sections being graduated to 75 fit nuts of varying sizes. The base portion of the tool, shown in Fig. 2, is provided with a foot rule scale, graduated in inches and fractions thereof, while the inclined face shown at 11 is provided with a nail gage as 80 shown at 2¹/₂, 3¹/₂, etc., Fig. 1.

While the tool may be used for various purposes, it is particularly intended for use when removing or pulling out nails. The nail may first be started by forcing the 85 pointed end 5 of the tool under the head. The tool is then slipped under the head, as shown in Fig. 3, and the head is engaged by a claw-hammer, as shown at 12. The pry exerted by the claw-hammer against the inclined surface 11 exerts a straight pull on the nail, thereby permitting it to be removed without bending the same and without enlarging the nail hole or otherwise mutilating the material into which the nail has 90 been driven. The inclined plane presented for the reception of the claw-hammer, when this is used, is so arranged that nails of practically any size may be removed; for instance, when pulling a nail it is obvious 95 that the lower pointed end of the tool will first be employed and that the tool will be advanced under the hammer whenever a new hold is required.

The base section and the end of the head A forms a right angle which permits the tool to be employed as a square. The openings in the web sections permit it to be used as a wrench, while the grooves 7 and 8 permit the tool to be used when straightening 100 bent nails.

The tool may otherwise be used as a crow-

bar or pry when removing box covers, and may also be used as a chisel, a screwdriver, an anvil, etc.

The tool is rigid and substantial in construction, and while it is here described as constructed of cast steel or like material, I wish it understood that the materials and finish of the same may be such as the experience and judgment of the manufacturer 10 may dictate and varying conditions may demand.

Having thus described my invention, what I claim and desire to secure by Letters Patent is—

- 15 1. A tool for the purpose specified comprising a square head with a pair of triangular thin plates extending therefrom and terminating in thin edges, the sides of said plates being disposed in a common plane and similar edges thereof disposed in a common plane.
- 20 2. A tool of the character described com-

prising a square head with a pair of thin plates extending therefrom, said plates having the shape of a right triangle and their 25 ends terminating in thin edges, the sides of said plates being disposed in a common plane and similar edges thereof disposed in a common plane.

3. A device of the character described comprising a head member and a pair of triangular shaped plates forming an extension thereof, said plates being interspaced and extending parallel from end to end, said plates having exterior parallel surfaces 30 forming a continuation of the sides of the head.

In testimony whereof I have hereunto set my hand in the presence of two subscribing witnesses.

ADOLPHUS F. EDDY.
